United States Patent Office

Des. 181,553
Patented Nov. 26, 1957

181,553

ROTATABLE DISPLAY STAND

Lawton L. Shurtleff, Lafayette, Calif., assignor to Thorsen
Manufacturing Company, a corporation of California

Application February 11, 1957, Serial No. 44,834

Term of patent 14 years

(Cl. D80—9)

F i g. 1

F i g. 2

Figure 1 is a front perspective view of the rotatable display stand, showing my new design.

Figure 2 is a top view thereof.

I claim:

The ornamental design for a rotatable display stand, as shown.
